CLAIM

I claim the ornamental design for a pet bowl, as shown and described.

DESCRIPTION

FIG. 1 is a perspective view showing my design for a pet bowl;

FIG. 2 is a top plan view thereof;

FIG. 3 is an underside view thereof;

FIG. 4 is an east side elevation view thereof;

FIG. 5 is a west side elevation view thereof;

FIG. 6 is a north side elevation view thereof; and,

FIG. 7 is a south side elevation view thereof.
